1
ARITHMETIC CIRCUIT

BACKGROUND OF THE INVENTION

The present invention relates to an electronic circuit for arithmetic and more particularly an arithmetic circuit for use in generating or checking the check digit attached to the important codes of the input data to the electronic computer.

The arithmetic circuit of the present invention is comprising a multiplier circuit directly connected to an adder circuit in cascade and operates on the operands according to a predetermined operation program, thereby obtaining the result. In the input data of an electronic computer, the check digits are generally attached to the important codes such as customer codes in most cases. For example, a number which is determined by one arithmetic check process or method is attached to one code. That is, the code 4138 is attached with the number 1 so that it becomes 41381. When such code is used as a customer code, the mistakes or errors in the data processing can be detected when input data is prepared or when the data is fed into an electronic computer.

There have been known various arithmetic check processes or methods. For example, the digits of 4138 are added and the least significant digit of the sum is utilized as check digit. That is, $4+1+3+8=16$ so that the check digit is six. However, when the correct code of 41386 is erroneously coded as 41836 in data processing, this error can not be detected by the above process. Such digit error is frequently made by a data processing operator. Therefore, the weights are normally multiplied by each digit of the code number and the least significant digit of the sum is utilized as the check digit. For example, assuming that the weights for digits of the code number 4138 be (7, 6, 5, 4),

$$(4, 1, 3, 8) \times (7, 6, 5, 4) = (28, 6, 15, 32)$$

so that the sum

$$28+6+15+32=81.$$

Therefore, the check digit is one so that the customer's code become 41381. In this case, the next least significant digits have no significance in obtaining the least significant digit of the sum of 28+6+15+32 so that the calculation may be carried out in a simple form of

$$8+6+5+2=21.$$

This method or process will be referred to as "first method" hereinafter.

Another process or method is such that instead of

$$28+6+15+32$$

each digit is added, that is

$$2+8+6+1+5+3+2=27$$

and the least significant digit of the sum 27, that is seven is utilized as the check digit. This process or method will be referred to as "second method" hereinafter.

The present invention is to provide an arithmetic circuit for providing or checking the check digit as described above.

SUMMARY OF THE INVENTION

The present invention relates to an arithmetic circuit for providing the check digit of the type described above by performing the above-described single decimal digit multiplication and addition and is comprising a multiplier circuit directly coupled to an adder circuit in cascade.

Generally the above first method can be expressed in the following equation:

$$D = R_{10} \left(\sum_{i=1}^n R_{10}(a_i \cdot w_i) \right)$$

where D = check digit,

$a_1, a_2, \dots, a_n$ = numbers of digits of an original code,

$w_1, w_2, \dots, w_n$ = weights for digits $a_1, a_2, \dots, a_n$,

N = decimal number of the original code,

$C_{10}(N)$ = quotient after division of N by 10 and

$R_{10}(N)$ = remainder. The second method can be expressed in the form of

$$D = R_{10} \left(\sum_{i=1}^n (R_{10}(a_i \cdot w_i) - C_{10}(a_i \cdot w_i)) \right)$$

2

The determination of D and w_i is made based upon the statistical analysis of input data errors. Since the method of this determination forms no part of the present invention, no description will be made in the specification. A group parity code attached to a group of codes is 1 in binary number and since the weights are identical misarrangement of digits can not be detected. The circuit which can perform the addition and multiplication must be provided in order to detect even the misarrangement in digits. Such detection cannot be easily effected by the conventional circuit. It is especially useless to detect the data errors by the electronic computer so that it is preferable to detect such errors in input data processing. The circuit of the present invention is a circuit which can be attached to an input machine.

15 The above and other objects, features and advantages of the present invention will become more apparent from the following description taken in conjunction with the accompanying drawing.

BRIEF DESCRIPTION OF DRAWING

FIG. 1 is a block diagram of one embodiment of the present invention; and

FIG. 2 is a detailed view thereof. DESCRIPTION OF THE PREFERRED EMBODIMENT

Referring now to FIG. 1, each digit of the number of the original code and its weights are applied to registers R_N and R_W from their terminals N and W respectively. The contents in the registers R_N and R_W are multiplied in a multiplier matrix M and the least significant digit of the result is transferred to a register R_M . In a register R_A is stored the least significant digit of the previous multiplication. The contents in R_M and R_A are added in an adder matrix A and the result is transferred to the register R_A again through a gate G when a signal C is applied.

35 In the similar manner, each digit of the original code and its weight are applied to the register R_N and R_W , thereby obtaining a check digit D.

FIG. 2 is a detailed view of the block diagram of FIG. 1 which is the circuit for representing a decimal number in 4-bit BCD.

40 Let it be assumed that a number 9 (1001) is applied through terminals n_4 to n_1 while a number 9 (1001), through terminals w_4 to w_1 . The registers R_N and R_W each having four bits are set by these numbers so that $N_0 (=n_1 \cdot \bar{n}_3 \cdot n_4)$ and $W_9 (=w_1 \cdot \bar{w}_3 \cdot w_4)$ are selected. Thereafter, multiplication, decoding and encoding are carried out in the matrix M and (0001) is derived from terminals μ_4 to μ_1 . That is the binary code of the least significant digit of the result 81 of 9×9 is obtained. This result is transferred to the register R_M .

45 This will be described in more detail with reference to other number. When number 2 is applied to the register R_N , N_2 becomes 1 (+E voltage). When number 6 is applied to R_W , W_6 becomes 1 (+E voltage). When N_2 is 1 and W_6 is 1, M_{26} becomes 1, thereby driving M_2 to 1. Therefore, μ_2 becomes 1. That is μ_4 to μ_1 become (0010) which is 2 in the decimal number. This means that the least significant digit of the result of $2 \times 6 = 12$, that is two is represented in the binary number.

50 As described above, the terminals M_{ij} (M_{11} to M_{19} , M_{21} to M_{29} , ..., M_{91} to M_{99}) of the matrix M are decoding terminals whose outputs are determined by the inputs to the registers R_N and R_W . The terminals M_K (M_0 to M_9) are encoding terminals selected by the sequence of connection of diodes from the terminals M_{ij} . The terminals μ_4 to μ_1 are parallel output terminals. Therefore, in the matrix M, multiplication, decoding and encoding are carried out and the results are obtained in the form of the binary code at the output terminals.

55 The results obtained at the terminals μ_4 to μ_1 sets the register R_M , thereby selecting one of the terminals A_K (A_0 to A_9) of the matrix A. For example, when the outputs of the terminals μ_4 to μ_1 are 0001 (=1 in decimal number), the terminal A_1 becomes 1 (+E voltage).

60 In this case, if 6 is stored in the register R_A , S_6 of S_K (S_0 to S_9) becomes 1 so that among their terminals A_{ij} (A_{00} to A_{09} , A_{10} to A_{19} , ..., A_{90} to A_{99}) A_{16} becomes 1 so that among S_K , (S_1 , to S'_1), S'_1 becomes 1. Therefore, the result of addition 7 (0111) are derived from the terminals α_4 to α_1 .

As described above, the terminals A_{ij} are the decoding terminals which are set in response to the inputs to the register R_M and R_A ; the terminals S_K' are the encoding terminals whose outputs are determined by a sequence of connection of diodes from the terminals A_{ij} ; and α_4 to α_1 are the parallel output terminals. Therefore, the addition, decoding and encoding are carried out in the matrix A and the results are derived from the output terminals in the form of a binary code.

The outputs from the terminals α_4 to α_1 set the register R_A upon arrival of the pulse signal C which opens the gate G . Therefore, in the register R_A is stored 7 (=1+6).

The above-discussed operations are cycled for each digit of the original code and the weights and after all operations, the check digit D is obtained.

The matrix M has been shown as being the matrix for carrying out the addition of the least significant digits, that is $9 \times 9 = 81 \rightarrow 1$. However, the second method of adding the least significant digit and the next least significant digit, that is $9 \times 9 = 81 \rightarrow 8+1=9$, can be effected by changing the arrangement of diodes in the circuits. So far the invention has been described with particular reference to the case in which the remainder after division of a number by 10 is utilized, but it will be easily seen that the remainder after division of a number by 11 may be also utilized by changing the sequences of connections of diodes from the decoding terminals M_{ij} of the matrix M to the encoding terminals M_K and from the matrix A_{ij} to the encoding terminals S_K' .

In the embodiment, the decoding terminals of the multiplier matrix M and the adder matrix A are provided for all combinations of the results of addition and multiplication, but the circuit which can operate the same function as that of the embodiment and whose size is about one-fourth of that of the embodiment may be realized by adding the complement coders at the input and output of the matrix.

According to the present invention, the output terminals of the multiplier circuit are directly coupled to the input terminals of the adder circuit so that both of the circuits are integrally connected in cascade so that the arithmetic circuit can be made simple in construction and compact in size. According to the present invention a multiplier circuit for single or individual decimal digit is connected in cascade so that the check digits can be easily provided. Furthermore, the results by the operation in the matrix are determined by the connec-

tions of the diodes from the decoding terminals to the encoding terminals so that the modifications of the design can be easily effected depending upon the process or method for providing different check digits.

The present invention has been so far described with particular reference to one embodiment thereof, but it will be understood that variations and modifications can be effected without departing from the true spirit of the present invention as described hereinafter and as defined in the appended claims.

I claim:

1. An arithmetic logic circuit for computing check digits for coded digital input signals, said circuit comprising:

a first register for receiving said input signals,

a diode matrix multiplier circuit connected to said first register for multiplying said digital input signals with weighting signals and providing outputs,

a diode matrix adder circuit with inputs effectively connected to said multiplier circuit for adding together outputs from said multiplier circuit with the contents of an accumulator register and providing outputs, and

gate means connected between outputs of said adder circuit and said accumulator register for passing the outputs of said adder circuit to said accumulator upon receipt of a gating signal thereby updating the contents of the accumulator.

2. An arithmetic circuit as in claim 1 further comprising a second register connected between the outputs of said multiplier circuit and the inputs of said adder circuit for sensing

30 the outputs of said multiplier circuit and driving the inputs of said adder circuit.

3. An arithmetic circuit as in claim 2 wherein said diode matrix multiplier circuit and said diode matrix adder circuit have a plurality of inputs and outputs representing the plural binary digits of a binary coded decimal digit, and further comprising

35 weighting input means connected to a group of inputs of said multiplier circuit whereby different weighting values may be multiplied with different coded decimal digits thus permitting each ordinal place of a coded decimal number to be differently weighted.

4. An arithmetic circuit as in claim 3 wherein said weighting input means comprises a register.
